EXPANSION ANCHOR SPRING BIASED
APART AT ENTERING ENDWarren J. Lewis, Mansfield, Ohio, assignor to The
Ohio Brass Company, Mansfield, Ohio, a cor-
poration of New Jersey

Application December 19, 1950, Serial No. 201,651

7 Claims. (Cl. 85—2.4)

1

This invention relates to expansion bolts and in particular to bolts intended and adapted to support the roofs of mines thus eliminating the use of costly and interfering supporting beams and posts.

The object of this invention is to provide a self-contained expansion bolt which may be inserted into a drilled opening in a mine roof and have both ends properly located relative thereto and having an initially spread but yieldable shell which may be collapsed to engage the side wall of the drilled opening with sufficient pressure to prevent the rotation of the shell relative to the wall of the opening when the stud is rotated to move the expander so as to increase the pressure of the shell against the whole wall sufficient to anchor the shell to the mine roof at a point well spaced from the surface of the roof.

This invention will be better understood from the specification which follows and reference to the drawing in which—

Fig. 1 is a side view of the bolt prior to positioning in a mine roof.

Fig. 2 is a side view of the bolt at 90 degree rotation from Fig. 1.

Fig. 3 is a top end view of Figs. 1 and 2 before insertion in a hole in a mine roof.

Fig. 4 represents the bolt as positioned in a hole in a mine roof prior to the expansion of the shell by the expander; the hole being drilled slightly larger than the fully collapsed diameter of the shell.

Fig. 5 is a sectional view on line 5—5 of Fig. 4.

Figs. 6 and 7 are two side views respectively of a spring member which functions in several ways as later explained.

This invention comprises a longitudinally split shell 1 with halves 2 and 3 which are pivotally hinged together at 4 which also holds them against relative longitudinal movement.

The inner surface 5 of each shell is tapered for a considerable length although they may be straight.

Positioned in the free or expandable end 6 of the shell is a tapered expander 7 provided with oppositely disposed guide wings 8. The expander is provided with a through axial-threaded opening 9 to receive a threaded stud 10.

The shell 1 is so constructed that a longitudinal slot 11 is provided between the edges of the halves 2 and 3 for substantially the length of the shell, and the balance of the edges of the halves meet as at 4.

The slot 11 acts as a guide for the expander 7, at least wings 8 may engage the edges of the shell 5.

2

halves and limit rotation of the expander relative to the shell when the stud 10 is rotated, if such cooperation is necessary.

The shell halves or sections 2 and 3 are each further slotted longitudinally as at 12 but these slots do not extend for the full length of the shell, but sufficiently to provide the shell with four expandable members and the lower portion of the shell is intact except for a shallow longitudinal groove 13 part way through the shell halves to receive the free ends 14 of a spring yoke 15.

The yoke 15 is assembled with the shell halves 2 and 3 by positioning the same in the slots 12 with the bight at the closed end projecting from the free end of the shell, and the free ends 14 of the yoke are positioned in the grooves 13 at the lower ends of the shell sections. The ends 14 are secured in the grooves 13 by peaning over the edges of the groove 13 onto the yoke ends. This attachment may be made by fusion between the parts but the heat is very apt to destroy the temper of the metal in the yoke ends.

In order to press the lower ends of the shell halves together and yieldingly maintain them together, the side arms 16 of the yoke 15 are formed non-parallel which brings the free ends 14 closer together than at the closed end of the yoke before the yoke is assembled with the shell sections.

The normal spacing between the ends 14 of the yoke is less than the diameter of the shell at its lower or hinged end.

The larger end of the expander is grooved on opposite sides to receive the yoke arms 16 and the closed end of the arms 16 is connected by the bight 17 arranged to be engaged by the expander when in its extreme upper position or by the end of the stud.

The stud 10 is threaded at one end to enter the threaded opening 18 in the expander and the lower end of the stud is provided with a head 19 and washer 20. The lower end of the stud may be threaded for a nut in place of the integral head.

The lower ends of the yoke are secured in fixed relation to their respective shell halves and act as a spring in a spring type hinge, that is, when the upper ends of the shell halves are pressed inwardly to the position shown in Fig. 4, a further tension is set up in the arms due to their being secured in fixed relation at both ends and this function is the same as set up in a spring on a spring type of hinge when the hinge parts are moved relative to each other, thus tending to return the shell halves to their original or normal position of Fig. 1.

Since the yoke arms 16 are interlocked with

the expander and they are also secured to the shell halves at their lower ends 14, and since the arms are not bendable in a rotational direction of the shell and expander due to their rectangular section, the arms 16 will act to prevent relative rotation of the parts but should the interlock between the yoke and expander become released, then the wings 8 will engage the shell sections as stated before and prevent relative rotation of the shell and expander.

After drilling a hole in the mine roof sufficient to take the shell 1 when the upper end is collapsed, the operator collapses the upper end of the shell and inserts the closed or upper end into the opening in the mine roof and then by pushing on the stud the expander is pressed against the bight 17 of the yoke thereby shoving the shell and expander into position until the washer 20 engages the mine roof.

The operator then rotates the stud in the proper direction, usually clockwise, which starts the expander 7 moving into the shell (see Fig. 4), but friction or the interlock between the expander and shell does not effect relative rotation between the shell and wall of the drilled hole in the roof because of the pressure of the shell halves against the wall, and the expander having limited or no rotation relative to the shell, the expander cannot rotate with the rotation of the stud, hence the expander is drawn into the shell, expanding the same into secure engagement with the roof and at the same time the washer 20 is drawn tightly against the mine roof.

By assembling the parts so that the stud 10 engages the bight 17 and the washer 20 engages the mine roof, the shell 1 is held against a downward movement relative to the wall of the opening as the expander is drawn into the shell.

The arms 16 of the yoke are parallel in their assembled relation to the shell, therefore the expander slides freely with respect to the yoke.

If the expander is drawn into the shell a sufficient distance in effecting a grip upon the wall of the opening, then the lower end of the shell will yield permitting the shell sections to grip the wall their full length.

The yoke maintains the parts in their assembled relation prior to installation of the bolt. Having described and illustrated my invention what I wish to protect is set forth in the following claims.

I claim—

1. An expander anchor for a bolt comprising a shell formed of radially movable sections the upper ends of which are not connected with one another, a threaded expander adapted to be attached to the upper end of a threaded stud to move the expander longitudinally of the shell to force the sections into engagement with the wall of a prepared opening, yoke-shaped spring means having its open end down and secured to the lower ends of the shell sections and its bight bridging the sections at the upper end thereof, said spring means normally and yieldably holding the upper ends of the shell sections in a spread apart relation, whereby the normally spread-apart upper ends of the shell sections may be moved radially inwardly against the tension of the spring and thereby be made to enter the said opening and to engage the wall of the opening by tension of the spring and thereby preventing rotation of the shell relative to the said wall when the stud is rotated.

2. An expander anchor for a bolt comprising an expanded shell formed of a plurality of sepa-

rate shell sections, the ends of the shell sections which are adapted to enter an opening first being referred to herein as the upper ends, and the opposite ends being the lower ends, spring means normally holding the lower ends of the shell sections yieldably together and the upper ends of the shell sections normally spread apart but movable radially inwardly to enter a drilled opening, a threaded movable expander at least a part of which is within the upper ends of the shell sections and is normally positioned to cooperate with a threaded stud when located between the shell sections whereby after said upper ends of the shell sections have been moved radially inwardly by manual means and then moved radially outwardly by said spring means into engagement with the wall of the drilled opening, the shell sections may be further spread apart by the expander when the stud is rotated and the expander is thereby drawn toward the lower end of the shell sections.

3. An expander anchor for a bolt comprising a shell formed of radially movable sections the upper ends of which are not connected with one another, a threaded expander adapted to be attached to the upper end of a threaded stud to move the expander longitudinally of the shell to force the sections into engagement with the wall of a prepared opening, yoke-shaped spring means with its side arms extending longitudinally along the shell and its bight bridging the upper end of the shell and engageable by the expander to facilitate positioning the shell in the prepared opening, said spring means normally and yieldably holding the upper ends of the shell sections in a spread apart relation, whereby the normally spread-apart upper ends of the shell sections may be moved radially inwardly against the tension of the spring and thereby be made to enter the said opening and to engage the wall of the opening by tension of the spring and thereby preventing rotation of the shell relative to the said wall when the stud is rotated.

4. An expander anchor for a bolt comprising two separate shell sections each of which is relatively thick at its lower end and relatively thin at its upper end, the edges of the sections shaped so as to permit lower portions thereof to meet, a slot extending up the middle of each section above a lower portion thereof, a spring yoke with its arms located generally within the slots and the lower ends of the arms fastened to the lower portions of the respective shells below the slots, the yoke normally holding the lower ends of the shell sections with their edges substantially meeting and the upper ends of the sections normally spaced apart with the outside periphery thereof greater than the outside periphery of the lower ends with their edges meeting but with the upper ends compressible to an outside periphery not substantially greater than said outside periphery of the lower ends of the sections, the bight of the yoke positioned above the sections, and a longitudinally movable expander held within the space defined by the projecting portion of the yoke and the inner surfaces of the upper ends of the sections and engaged with the yoke so as to be non-rotatable relative to the sections and to expand the sections when the expander moves downwardly toward the lower ends of the shell sections.

5. An expander bolt which includes a stud with an expander threaded on its upper end, a hollow shell formed of two separate sections with the expander originally disposed adjacent the upper

5

ends thereof, a separately formed yoke-shaped spring with its bight spaced longitudinally from the upper end of the shell and engageable by either an end of the expander or the upper end of the stud, a portion of the side arms of the yoke-shaped spring being substantially coextensive with the shell sections, oppositely disposed means extending longitudinally along each shell section to receive the said coextensive portion of the side arms of the yoke-shaped spring, the upper ends of the shell sections being tapered thinner than the lower ends thereof, the lower end of each shell section encircling substantially one-half of the stud, each shell section being secured to one of the side arms of the spring yoke at the lower end of the shell thereby forcing the lower ends of the sections inwardly toward the stud and simultaneously forcing the upper ends of the sections radially outward away from the stud so that the normal outer periphery of the upper end of the shell is greater than the normal outside periphery of its lower end, the upper ends of the shell sections being adapted to be moved inwardly toward the stud against the tension of the yoke-shaped spring to reduce the periphery of the shell sufficiently to enter a prepared opening for the bolt.

6. In an expansion bolt comprising a threaded stud, a shell formed of a plurality of separately formed radially movable sections, a threaded expander in combination with the threaded upper end of the stud to move the expander longitudinally of the shell from the upper end toward the lower end to force the sections into engagement with the wall of a prepared opening when the stud is rotated in one direction, the expander being tapered and the upper end of the shell sections being thinner than at the lower end thereby forming a tapered inner surface engageable by the expander, the shell sections having oppositely disposed longitudinal means associated with each shell section and extending substantially the entire length of the shell, the combination with the shell of an elongated spring yoke, the arms of the yoke positioned in the said longitudinal means and having their free ends secured to the shell sections at the lower end of the shell, whereby the lower ends of the shell sections are

6

normally held in yieldable pivotal relation and the upper ends of the shell sections are normally and yieldably held in spaced-apart relation, the arms of the spring yoke extending beyond the upper end of the shell with the bight at the closed end of the spring yoke adapted to be engaged by either the expander or the end of the stud to assist in the positioning of the bolt in the opening.

- 10 7. An expansion bolt which includes a stud with an expander threaded on its upper end, grooves in opposite sides of the expander in its outer surface, two shell sections, each slotted from its upper end to near its lower end, a spring 15 yoke with its bight over the upper end of the stud and its sides located in the grooves and slideable longitudinally therein, inner portions of the sides of the spring yoke being located in the slots, the upper ends of the shell sections being 20 tapered thinner than the lower ends, the lower end of each shell section extending half way around the stud, each shell section being fastened to one side of the spring yoke with the lower end of the section adjacent the stud and its upper end 25 away from the stud so that the outside periphery of the upper end of the shell is greater than the outside periphery of its lower end, the upper ends of the shell sections being adapted to be pressed toward the stud against the action of the spring 30 yoke to make their outside periphery substantially the same as the outside periphery of their lower ends.
